UNITED STATES PATENT OFFICE.

STEPHEN DE GAETANO, OF BROOKLYN, ASSIGNOR TO HUGH W. COLLENDER,
OF NEW YORK, N. Y.

POOL-BALL FRAME.

SPECIFICATION forming part of Letters Patent No. 228,879, dated June 15, 1880.

Application filed March 25, 1880. (No model.)

To all whom it may concern:

Be it known that I, STEPHEN DE GAETANO, of Brooklyn, in the county of Kings and State of New York, have invented an Improvement 5 in Triangles or Pool-Ball Frames; and I do hereby declare that the following is a full and exact description thereof, reference being had to the accompanying drawings, making part of this specification.

Previous to my invention it has been customary to make the triangular ball-holders used in placing the balls for the game of "fifteen-ball pool" (and other games played with fifteen balls) on billiard tables of three straight strips 10 or pieces of wood joined at their adjacent ends to form the angles of the frame, and to strengthen the frame at these angles by interiorly-placed corner-blocks, glued or otherwise fastened in, and sometimes to further strengthen 15 the angles or corners by metallic angle-plates applied exteriorly to the frame. It is very desirable to have these ball-frames or triangles made as light as possible, and at the same time sufficiently strong and durable to withstand 20 the usage and accidental strains and jars to which they are necessarily subjected, and, constructed as they usually have been, they have been found inadequate in strength when made reasonably light. More than this, it has 25 been found in practice that there is great liability of injury to the cloths of the tables from any accidental fall (from the hand of the game-keeper) of the triangle on the table with one of its corners or angles striking first, the latter being apt to cut or mar the cloth. More 30 especially is this so in the use of triangles having the metallic exterior corner-plates, and the latter are used always by some manufacturers. 35 My invention has for its object to produce a "triangle" or ball-frame which can be made much lighter, and also much stronger and more durable, than those heretofore manufactured, while at the same time its manufacture can be 40 accomplished at much less cost than that of the construction or kind of frames heretofore made, and in its use it will be free of all the objections found in the use of the old-fashioned ball-frame.

To these ends and objects my invention consists in a triangle or ball-frame composed of several layers or thin strips of wood bent round into the requisite shape and glued (or otherwise fastened) together, all as will be hereinafter more fully explained. 50

To enable those skilled in the art to make and use my invention, I will proceed to more fully describe it, referring by letters to the accompanying drawings, making part of this specification, and in which I have shown a 60 ball-frame made as suggested above, and have also illustrated the previous mode of construction of triangles.

Figure 1 is a plan view of my new frame, representing it as in use on a billiard-table 65 for the purpose of properly placing the fifteen balls for starting the game of pool. Fig. 2 is a side or edge view of the same; and Fig. 3 is a horizontal section of the frame, taken at the line *xx* of Fig. 2. Figs. 4 and 5 are respectively a partial top and edge view of the old-fashioned triangle. 70

From Figs. 1, 2, and 3 it will be seen that my new frame is composed of several or numerous strips or thin layers of wood, or of several strips of veneer, which are placed in close contact and perfectly united throughout their lengths, by preference in such an arrangement that no two of the end jointures of the strips occur at the same locality. 75

As clearly shown in Figs. 1, 2, and 3 of the drawings, my improved ball-frame, instead of having angles, has three rounded corners, so to speak, the circular curvature of each of which (at the inner surface of the frame) 80 should correspond substantially with the curvature of the pool-ball, so that in use the foremost ball (that one designed to be placed on the "spot" of the table) will fit into the front curved corner of the frame and the two rear-most and outer balls will fit into the rear curved frame-corners, whereby not only will the placement of all the balls in the proper relative arrangement be effected, but an accurate placement of the foremost ball on the 85 spot will be more certainly and readily effected, since the proper position of this ball can be better regulated by the game-keeper than with 90 95

the use of a frame the foremost corner of which projects farther beyond the spot and in the form of an acute angle.

By preference the several layers or strips 5 of wood composing the frame have their ends joined, as seen at *a b c*, Fig. 3, at different localities, so as to break joints, whereby greater strength and durability in the aggregation are attained. In the manufacture thus of the frame 10 the several layers of wood may be either successively bent round the outside of a properly-shaped former and be clamped thereon by any proper means, or they may be placed within a proper shaped female former and be forced 15 and held therein by means of an expanding interior clamping device or other means, the method and means of manufacture being immaterial to my invention so long as by them the product shall be a frame of the proper 20 shape formed of a series of bent strips of thin wood, the ends of each of which are brought together, and all of which are securely united superficially to each other.

By the formation thus of the frame it will 25 be seen all angles or sharp corners are avoided, and the frame is made practically of a continuous band, (or hoop-like,) instead of with three separate pieces joined at the three corners.

The use of several layers or strips glued together, with the directions of the grain of wood naturally varying, of course renders the structure stronger than it would be if made of a single thickness bent round into shape, while the formation of the frame thus of the several 35 very thin strips of wood in lieu of one thick strip avoids the undue strain that would necessarily arise at the corner bends of a thick strip, and the consequent liability of any fracture or split in the wood at such localities; and 40 not only is my improved frame therefore much stronger, more durable, and in all other respects more desirable than the kind heretofore made, but it is so extremely light and of such form that no blow struck the cloth by letting 45 the frame fall on the table can harm the latter

in the least, while at the same time the cost of manufacture is so infinitely less that the improved frame can be sold for about one-fifth the price of the less desirable one. Indeed, they can be sold at this reduction of price 50 when made with outer veneers of some handsome and expensive wood, as against the old-fashioned construction of frame made of very cheap wood.

A careful observation of Figs. 4 and 5 will 55 show that the hand-labor necessary only for the adaptation to and securement on frame of the interior corner-blocks, *g*, and metal angle-plates or shoe-pieces *h* must far exceed the cost of manufacture of my entire contrivance, the 60 stock of which may be all gotten out by machinery, and only requires to be bent round a former and have the several layers cemented together. The height of the frame (that is, the width of the bands or strips composing it) is 65 of course about the same as that of the usual ball-frame.

Having now sufficiently explained the construction and character of my improved ball-frame to enable any one skilled in the art to 70 which my invention relates to make and use my said invention, what I claim as new, and desire to secure by Letters Patent, is—

1. A ball-frame or triangle composed of wood or other suitable material and formed 75 with three interior and exterior curved or rounded corners, substantially as and for the purposes set forth.

2. A ball-frame having curved or rounded corners and made of a series of layers of wood 80 bent into triangular shape and having their adjacent surfaces glued or otherwise fastened together, as and for the purposes set forth.

In witness whereof I have hereunto set my hand this 15th day of March, 1880.

STEPHEN DE GAETANO.

In presence of—

ISAAC McDUGAL,
Wm. H. WIGGINS.
